UNITED STATES PATENT OFFICE.

ANDREW RASMUSSEN, OF RACINE JUNCTION, WISCONSIN, ASSIGNOR TO PEERLESS
SILO SUPPLY CO., OF RACINE, WISCONSIN, A CORPORATION OF WISCONSIN.

HOOP FOR SILOS AND LIKE TANKS.

1,141,413.

Specification of Letters Patent.

Patented June 1, 1915.

Application filed March 13, 1914. Serial No. 824,865.

To all whom it may concern:

Be it known that I, ANDREW RASMUSSEN, a citizen of the United States, and a resident of Racine Junction, in the county of Racine 5 and State of Wisconsin, have invented certain new and useful Improvements in Hoops for Silos and like Tanks; and I do hereby declare that the following is a full, clear, and exact description thereof, reference being had to the accompanying drawings, and to the characters of reference marked thereon, which form a part of this specification.

This invention relates to improvements in 15 hoops and hoop fasteners for silos and like tanks or tubs, and more especially to such tanks or receptacles of which the walls are made of matched staves.

Among the objects of the invention is to provide a hoop or encircling member for 20 such tanks and the like of a construction which may be readily applied to and formed on the tank without the necessity of preliminarily forming same.

A further object of the invention is to provide a hoop or encircling member of this 25 character which is convenient to handle and ship.

Other objects of the invention are to improve and simplify hoops and encircling 30 members for silos and like tanks, and the invention consists in the matters hereinafter set forth and more particularly pointed out in the appended claims.

In the drawings:—Figure 1 is a horizontal 35 section of a tank provided with a hoop and hoop fasteners embodying my invention. Fig. 2 is a fragmentary side elevation thereof. Fig. 3 is a sectional detail on the line 3—3 of Fig. 2. Fig. 4 is a side elevation of 40 one of the hoop sections. Fig. 5 is an end view of one of the end fittings constituting part of the hoop section or member.

As shown in the drawings, 10 designates the wall of the silo tank or inclosure, made 45 up of matched staves in the usual or any preferred manner, and 11 designates, as a whole, the hoops or encircling members which surround or encircle the tank.

12, 12 designate hoop tighteners or fasteners 50 which coöperate with the hoops to suitably fasten the same about the tank wall. Ordinarily each hoop will include two or more like sections and two or more tighteners 12.

55 In accordance with one feature of my in-

vention the hoop, whether it consists of a single length or section or of a number of sections, consists of flexible twin members 13, 13 and end fittings 14, 14 to which the ends of said twin members 13 are connected. 60 The said twin hoop members may be applied in any suitable manner to the end fittings. As herein shown each of the twin members extend through longitudinal openings 15 in the end fittings and are turned 65 back to form hooks 16 which are seated in other openings 17 in the end fittings. The said end fittings are further provided with openings 18 through which the hoop tighteners 12 extend and by which the ends of the 70 said hoop or the ends of the adjoining sections are fastened together. As herein shown, said hoop fasteners consist of headed bolts screw-threaded to receive nuts 19 by which the end fittings are drawn together 75 to tighten the hoop sections about the tank walls. Preferably the said openings in the end fittings through which the hoop tighteners extend are elongated transversely of said 80 fittings and are also larger in all dimensions 85 than the exterior diameter of the bolts so as to permit said fittings and bolts to adapt themselves to each other and to the wall of the tank. In order that the said end fittings may be made as light as possible, consistent 85 with ample strength, the said transverse openings 18 may be formed partially in the ribs 20 on the exterior side faces of the end fittings, as shown in Fig. 5.

As shown in Fig. 1, each hoop is made of 90 three sections. This arrangement, however, may be varied to accord with the diameter of the tank or other conditions. I have not herein shown the detail of the hoop connectors at the door of the silo, but such detail may be arranged in any suitable or preferred manner as, for instance, in the manner shown in my pending application for U. S. Letters Patent, Serial No. 806,161, filed on December 12th, 1913. Moreover, springs 95 100 may be interposed in the said hoop in the manner shown in said prior application or otherwise, for the purpose set forth in said application.

An important advantage of the construction described is that the twin members 13 constituting the hoop or hoop sections, and which are vertically spaced on the tank wall, may be made of a diameter which permits them to be sufficiently flexible to allow the 110

hoop to be readily applied to and formed on the tank wall, and to lie closely upon or cling to the said wall. Heretofore, it has been a common practice to make hoops of a single round shape, and in practice, in order to secure the required tensile strength, it is necessary to make such shapes of a diameter not readily flexible. It has, therefore, been the common practice to form or curve said 10 hoops or hoop sections by a suitable forming machine so as to adapt the same to tanks of a given or substantially known diameter in order that said hoops may be applied with approximate accuracy to the tank. 15 This practice results in the necessary expense of forming the hoops and also results in producing a curved hoop section to be transported from the factory to the field of a shape which is inconvenient to handle, 20 ship and store.

The hoop construction herein shown is superior to flat or band hoops sometimes used, in that there is avoided the disadvantage resulting from band hoops wherein 25 there is a tendency for moisture to collect between the hoops and the staves which tends to promote decay of the staves and rusting of the bands.

In practice the hoop tightening members 30 12 may be made of relatively weaker tensile strength than the twin members 13 of the hoop and, therefore, most likely to part under tensile strain. However, such tighteners may consist of ordinary machine bolts 35 and are therefore, very readily replaceable as compared to the replacement or repair of rods or bands heretofore employed. The breakage of the threaded ends of the hoops necessitates that they be taken to a blacksmith shop for straightening, welding and 40 recurring, obviously at an expenditure of considerable time and labor.

Another advantage of the construction described is that all parts of the hoops may be 45 readily made or formed in an ordinary well equipped blacksmith's shop, with the exception of the end fittings which constitute the only parts that are necessary to be provided by the manufacturer. Thus, in locations where the freight rate is a disadvantage against the shipment of the entire hoop structure, the hoops may be principally furnished by the local blacksmith or machine shop upon receiving the end fittings to which 50 the hoop members 13 and the tighteners 12 are adaptable. A further advantage of the

construction described is that a central pull is exerted on the twin hoop members 13 by reason of the fact that the tightening bolts 12 are disposed centrally of the said hoop 60 members. Thus the pull on the hoop members is equalized.

I claim as my invention:—

1. A hoop for a silo and like tank comprising a plurality of sections arranged end 65 to end and constituting the principal length of the hoop, each section consisting of separate twin hoop members and end fittings to the opposite sides of which the ends of the hoop members are attached, and hoop tight- 70 eners extending between and attached to adjacent end sections between the ends of the twin members to draw the hoops together and to equalize the tensioning of the 75 hoop members about the tank.

2. A hoop for a silo and other tanks comprising separate twin hoop members, constituting the principal length of the hoop, fittings extending across the ends of said members and provided at opposite sides 80 with openings to receive the ends of the hoop members, whereby they are attached to said fittings, said fittings being provided centrally between said openings with other openings to receive a tension member, and a 85 tension member extending through the latter openings to draw the hoop ends together and to equalize the tensioning of the hoop members about the tank.

3. A hoop for a silo and other tanks composed of twin hoop members, fittings at the ends thereof, said fittings being provided with openings through which said members extend and provided with other openings, and the ends of the members being bent 95 back upon themselves to enter said latter openings, whereby to attach said members to said fittings, said fittings being further provided between the twin members with other openings and hoop fasteners extending through the latter openings to draw the 100 hoop ends together and to tighten the hoop about the tank.

In testimony, that I claim the foregoing as my invention I affix my signature in 105 the presence of two witnesses, this 6th day of March, A. D. 1914.

ANDREW RASMUSSEN.
